UNITED STATES PATENT OFFICE.

BYRD OLIVER YEARWOOD AND ROBERT CUTTLER PATTISON, OF PORTSMOUTH, VIRGINIA,
ASSIGNORS OF ONE-FOURTH TO EDWARD SCHAEFER, OF TOCCOA, GEORGIA.

AUTOMATIC CYLINDER RELIEF AND VACUUM VALVE.

No. 903,530.

Specification of Letters Patent.

Patented Nov. 10, 1908.

Application filed May 15, 1908. Serial No. 433,085.

To all whom it may concern:

Be it known that we, BYRD O. YEARWOOD and ROBERT C. PATTISON, citizens of the United States, residing at Portsmouth, in the county of Norfolk and State of Virginia, have invented a new and useful Automatic Cylinder Relief and Vacuum Valve, of which the following is a specification.

This invention has reference to improvements in automatic relief and vacuum valves, and is designed more particularly for use in connection with the cylinders of locomotive engines, although applicable to other uses.

The purpose of the present invention is to relieve any excess pressure in the engine cylinder due to water or vacuum therein, so that when an engine is drifting the reciprocating piston will not cause a vacuum on one side and produce undue or excess pressure on the other side, but the two ends of the cylinder will be connected together or to the external atmosphere so that the pressure is relieved and the tendency to form a vacuum is destroyed.

The invention comprises a valve structure in which springs are omitted since they are liable to become corroded or get out of order, and the valve is so constructed that the initial pressure of steam in the steam chest will seat the valve and hold it in its seat while differential pressure between the steam chest side and cylinder side of the valve results in the valve remaining wide open when the engine is drifting.

The inventor will be best understood from a consideration of the following detailed description taken in connection with the accompanying drawings forming a part of this specification, in which drawings

Figure 1 is a longitudinal section of a valve constructed in accordance with the present invention. Fig. 2 is a section on the line A—B of Fig. 1. Fig. 3 is a side elevation of an engine cylinder and adjacent parts showing two connected valves at the two ends of the cylinder. Fig. 4 is an end elevation of the structure shown in Fig. 3. Fig. 5 is an end elevation of a modified form of the invention. Fig. 6 is a front elevation of the construction shown in Fig. 5 with parts in section.

Referring to the drawing, and more particularly to Fig. 1, there is shown a cylinder 1 constituting the body of the valve, and at one end this cylinder is formed into a neck 3 threaded on the exterior for a distance as indicated at 4 for a purpose which will presently appear. On the interior of the cylinder 1 where it joins the neck 3, there is formed an annular flange or ledge 5 on one face of which there is formed a valve seat 6 to which reference will presently be made. On one side of the cylinder 1 is formed a base or support 7 internally threaded as indicated at 8 to receive a threaded nipple by means of which the valve is connected to the casing 9 between the power cylinder 10 of the engine and the piston valve cylinder 11 in the particular structure illustrated in Figs. 3 and 4. The interior of the base or support 7 communicates with the interior of the cylinder 1 through a suitable port 12. Projecting from one side of the cylinder 1 near the end remote from the neck 3 is a boss 13 internally threaded for the reception of a pipe 14 and communicating with the interior of the cylinder 1 through a port 15. The end of the cylinder 1 remote from the neck 3 is closed by a head 16 securely bolted in place so as to be steam tight with the corresponding end of the cylinder 1. Formed on the inner face of the head 16 is a central projecting member 17 entering the interior of the cylinder 1 for a distance and located concentric therewith. The projecting member 17 receives an annular piston 18 entering the annular chamber 19 formed between the outer walls of the extension 17 and the inner wall of the cylinder 1. On the outer face of the cylinder 18 are a number of ribs 20 in which are formed annular grooves 21 for the reception of packing rings 22 and in the outer face of the projection 17 are annular grooves 23 receiving packing rings 24 which bear against the inner face of the piston 18, where it moves upon the outer face of said projection 17. The piston 18 at the end remote from the head 16 is formed with a valve seat 25 shaped to engage the seat 6 when the piston is moved toward the right as viewed in Fig. 1. The chamber 19 is in free communication with the pipe 14 through the port 15, while the interior of

the cylindrical piston 18 beyond that portion entered by the projection 17 is in free communication with the interior of the neck 3 and when the piston 18 is moved away from the valve seat 6 then the port 12 is also in free communication with the interior of the neck 3. There are provided two valves for the two ends of the cylinder 10, one valve being located at one end of the cylinder 10 and the other valve at the other end, and the pipe 14 of these two valves have a common connection 26 with the live steam side of the piston valve or steam chest 11. It is to be observed that the end wall 27 of the piston 18 is within the chamber 19 and the opposite end wall 28 communicates with the port 12. Suppose now that steam is admitted to the steam chest for the purpose of driving the main engine. The live steam pressure is exerted against the end wall 27 of the piston 18, since the chamber 19 is at all times in communication with the live steam side of the steam chest 11. The piston 18 is immediately forced toward the right as shown in Fig. 1, until the valve 25 is firmly seated against the valve seat 6 and the port 12 is thereby closed. Any live steam pressure within the cylinder 10 is unable to move the piston 18 away from the seat 6, since the effective area of the wall 28 is less than the effective area of the wall 27 and consequently the valve piston 18 remains in the closed position so long as the locomotive engine is operating under normal conditions. If, now, steam be cut off from the steam chest and from the cylinder 10 and the engine be allowed to drift, the locomotive cylinder will force the valve open and the vacuum created in the steam connection will hold the valve open even against a greater vacuum in the locomotive cylinder, owing to the difference in area of the two end walls of the piston or valve 18. In practice, the area of the wall 27 is from fifteen per cent. to twenty per cent. greater than the effective area of the wall 28.

The valve forming the subject matter of the present invention is simple in construction and for its operation relies entirely on the presence or absence of steam pressure in the steam chest and will operate equally well under high and low steam pressures. The valve is applied as closely as possible to the steam ports so as to avoid a wasteful increase in clearance which is a natural defect in the piston valve engine. From a standpoint of economy in fuel, two valves are used in each cylinder, since if only one valve were used in each cylinder and were connected by the necessary pipe to the two steam ports, a large volume of steam, at boiler pressure would fill this pipe at each and every stroke of the piston when the engine is working under steam and then the volume of steam that fills the pipe is exhausted to the atmosphere

without having done any useful work. Furthermore, the valves open and close only when the locomotive throttle is opened or closed, and their life is thus greatly increased and the cost of repairs is correspondingly reduced.

In order to prevent any foreign matter from being drawn into the cylinder or the cylinder lubricant from being blown out to the atmosphere, and also to keep the cylinder walls warm so as to reduce the initial condensation in the cylinder when the locomotive throttle is reopened, after the engine has been drifting, the two valves are connected together by a pipe sufficiently large to carry the hot gases and air from one end of the cylinder to the other, and the reverse when the two valves remain open and the engine is drifting. The pipe is indicated in the drawing by the reference numeral 27', and at each end enters the corresponding neck 3 of a valve casing 1. The neck 3 where entered by the pipe 27' is suitably counterbored to receive a packing gland 28' and packing 29, while a flanged collar 30 is screwed upon the threaded portion 4 of the neck 3 and serves to hold the gland 28' and packing 29 in place.

So far as the operation of the valve is concerned in relieving the vacuum and pressure alternately created by the reciprocation of the engine piston, the pipe 27' may be omitted and the ends of the neck 3 remote from the casing 1 may be freely opened to the atmosphere. Under these conditions the air is simply drawn into the engine cylinder and again forced out on the return stroke of the piston, thereby preventing the vacuum or excessive back pressure in the locomotive cylinder, but the presence of the pipe 27' by preventing the initial condensation in the cylinders if the cylinder walls remain warm when the engine is drifting, results in a further saving of fuel.

It is to be observed that the valve consists of practically three parts, namely, the valve proper, the valve casing, the valve head, and all springs and other parts liable to corrosion or to get out of order are omitted, while the valve is operated entirely by the presence or absence of steam pressure.

When the engine is drifting, and the valves at the two ends of the cylinder have been forced open by the compression in the locomotive cylinder and are held open by the vacuum created in the steam cylinder, then there is an unobstructed passage from one end of the cylinder through the ports and connecting pipe to the other end of the cylinder so that the gases may freely flow back and forth as the piston reciprocates in the engine cylinder. The two relief valves, therefore, remain open, until the locomotive throttle is again open at which time the pres-

sure through the port 15 acting on the wall 27 of the valve piston 18 closes the valve. Should there occur at any time an excess of pressure in the engine cylinder then the 5 valve will automatically open and relieve such excess pressure.

The valve meets all the requirements of the piston valve and compound locomotive. The valve is particularly adapted to 10 pound engines since it readily adapts itself to the varying pressure that the high and low pressure cylinders are subjected to.

The principles upon which the relief valve are constructed are applicable to other 15 connections than the one shown in the drawing and it is to be understood that the invention is not limited to the exact construction and location of the parts illustrated and described, but these parts may be modified as 20 the necessities of service may demand. The valve is, also, applicable to the walls of the cylinder by boring a chamber in the walls of the cylinder connecting both live steam ports. The chamber or port will perform 25 the same function as the connecting pipe 27' between the valves and will, also, form the body or cage for the valve. This arrangement is shown in Figs. 5 and 6, where the connecting port is indicated at 31, and the 30 live steam ports indicated at 32 communicating at each end with the connecting port 31. At the ends of the connecting port or passage 31 the walls of the cylinder are counter-bored, as shown at 33, to receive a cylinder 34, housing the piston 18, while the 35 ends of the connecting port or passage 31 are formed into a valve seat 6 receiving the valve 26 on the end of the piston 18. The outer end of the cylinder 34 is carried to 40 a point flush with the end of the locomotive cylinder body and a head 16 is there applied with the central projecting member 17, as in the structure shown in Fig. 1. The cylinder 34 is provided with a port 35 corresponding to the port 15 of the structure of 45 Fig. 1, and this port is in communication through a pipe 14 with the live steam side of the steam chest.

It will be seen that the structure of Figs. 50 5 and 6 is the same as that of Figs. 1 to 4, except that the valves are entirely housed in the walls of the locomotive cylinder and the only exposed parts are the pipes 14 and 55 26. The operation is the same as that already described with reference to the structure of Figs. 1 to 4.

What is claimed is:—

1. A relief-valve mechanism for engine cylinders comprising a suitable differential 60 valve member at each end of the cylinder and in communication with the corresponding end of the interior thereof, a means of communication between the steam chest and

each valve on the side thereof remote from its seat, and means of free communication 65 between the valves at their seat ends.

2. An engine cylinder having formed in its walls at each end a receptacle having a valve seat, said receptacle communicating near one end with the interior of the cylinder at the respective end of the latter, and said cylinder also being formed with a channel connecting the two receptacles at the valve seat ends, and a valve in each receptacle, said receptacles having means of communication between the ends thereof remote from the valve seats and the steam chest of the cylinder.

3. A relief valve for engine cylinders comprising an annular open ended piston 80 or valve member, and a receptacle therefor having a valve seat near one end for the valve and a head at the other end provided with a central, inward projection, entering the annular piston, and along which the 85 piston or valve is movable, the said receptacle also having means of communication with the interior of the cylinder and with the live steam supply.

4. A relief valve for engine cylinders 90 comprising a differential valve at each end of the cylinder, and connected with the interior thereof, a means of communication between each valve and the steam chest, and a connection between the sides of the two 95 valves remote from that connected to the steam chest, for placing the two ends of the engine cylinder in communication when the valves are open.

5. A relief valve for engine cylinders 100 comprising a receptacle having one end constituting the exhaust end and adjacent thereto having a valve seat, means adjacent to the valve seat for connecting the receptacle to the interior of the engine cylinder, means 105 adjacent to the end of the receptacle remote from the valve seat for connecting the said receptacle with the steam chest of the cylinder, an annular open ended piston or valve housed in the receptacle and movable longitudinally therein and a closure for the 110 end of the receptacle remote from the valve seat, provided with an inward projection entering the piston or valve.

6. A relief valve for engine cylinders 115 comprising a receptacle having one end constituting the exhaust end, and adjacent thereto having a valve seat, means adjacent to the valve seat for connecting the receptacle with the interior of the engine cylinder 120 means adjacent to the end of the receptacle remote from the valve seat for connecting the said receptacle with the steam chest of the cylinder, an annular open ended piston or valve housed in the receptacle and movable longitudinally therein, and a closure for 125

the end of the receptacle remote from the valve seat, provided with an inward projection entering the piston or valve, the valve being provided with packing engaging the inner wall of the receptacle and the projection being provided with packing engaging the inner wall of the valve.

In testimony that we claim the foregoing

as our own, we have hereto affixed our signatures in the presence of two witnesses.
